ELECTRIC INSULATOR.

1,106,797.

Specification of Letters Patent. Patented Aug. 11, 1914.

Application filed February 24, 1913. Serial No. 750,223.

To all whom it may concern:

Be it known that we, JOHN L. FAY and SYLVESTER B. WAY, citizens of the United States, and residing, respectively, in the city of St. Louis, Missouri, and city of Milwaukee, State of Wisconsin, have invented certain new and useful Improvements in Electric Insulators, of which the following is a full, clear, and exact description, such as will enable others skilled in the art to which it appertains to make and use the same, reference being had to the accompanying drawings, forming part of this specification, in which—

15 Figure 1 is a detail view illustrating my improved insulator in position. Fig. 2 is a sectional view through our improved insulator. Fig. 3 is an end elevation of Fig. 2.

This invention relates to new and useful 20 improvements in electric insulators designed particularly for use in supporting line wire conductors conveying electricity at high potential.

Our improvement is designed particularly 25 to avoid the "flash over" incident to the transmission of energy at high voltages and may be used alone or in conjunction with a series of insulators arranged in tandem and either at the head, middle, or end of such 30 series. Our experience has been that the "flash overs" occur most frequently in warm weather when the atmosphere is humid, and we have accounted for these "flash overs" at this time by reasoning that atmospheric 35 conditions are conducive thereto. We have observed that the static electricity, which we believe is the immediate cause of the "flash overs", passes over the upper part of the insulating disk or bell characteristic of 40 insulators commonly used, and because of this, the metal of the inclosing shell at the back of the bell is burned on its upper side. The static charge on the conductor produces 45 an ionization of the air in the immediate vicinity of the insulators with the result that the metal portions of the insulator are surcharged with electricity and when a disturbing influence is present, such as a ground, sudden change of heavy load, out of balance 50 disturbances and the like, the "flash over" results.

During the "flash over" period, the air forms a conducting vapor, the dynamic current then flows from the line through the 55 ionized air to the metal parts of the insu-

lator attached to the tower. The result of the dynamic current is to produce an intense rise in temperature at the contact point of the arc, fusing the porcelain insulator between the metal cap on one side of 60 the insulator and the metal part on the inside of the insulator, carrying metal with it in its path, thereby reducing the insulator to a point where it is of no value as such. The several disks constituting the insulation 65 of the insulator unit may all be broken down successively which will result in rendering the transmission line inoperative. It is the purpose of our invention to avoid this difficulty by providing means whereby a 70 circulation of air will be induced to dissipate the heat produced by the discharges and sparking, and also to eliminate the ionized or partially broken down air produced by the presence of electrical stress 75 caused by oscillation and vibration of charging current, and by so doing, minimize the conditions which we believe are the immediate cause of "flash overs". It is also 80 our purpose to provide an insulator which will not be injured by "flash overs" and which will perform the dual function of inserting in series with the potential applied to the insulators a spark gap which will consume a part of the disruptive force 85 of the power arc which may follow the flash over and thereby minimize the probability of such arc causing break downs in other disks; and leave in circuit, in case other disks do break down, an insulator which will 90 not be damaged incident to the most vicious flash over, and which will enable the line to be operated at least temporarily after 95 normal electric conditions have been restored on the line.

In the drawings, we have illustrated a form of insulator in which 1 is the hook or suspension member to which the line wire may be connected. This hook is embedded in a mass of porcelain 2, having an out- 100 standing flange 3 constituting the insulation disk.

4 is the metal cup embracing the hub of the porcelain disk, said hub having an eye or other means for the attachment of the 105 hook of the adjacent insulator if two or more insulators are employed.

5 is a metallic disk of any desired shape, that shown in the drawing being bell shaped with its lower portion cut away as at 6. 110

This metal shield is attached to the cup 4 before referred to, in any suitable manner, and preferably at its marginal edge radially removed from the insulation disk as shown.

5 7 is a corresponding metallic disk or shield which is secured to the hook 1 and preferably spaced apart from the shield 5 as shown. By this construction, it will be observed that heating of either of the disks 10 5 or 7 will induce a current of air to flow upwardly between them so that the circulating air will have a tendency to cool the disk; and that furthermore, the circulating air will tend to reduce the ionization of the 15 air around the insulating disk because of the constant displacement of the ionized air.

In connecting line wire 8 to hook 1, it is common practice to make use of what is generally known as a "dead end" connection, and provide a path around the insulator units by means of a loop 9 which produces an abrupt turn in the line conductor. It is well known that such a turn in an 20 electric conductor transmitting electric energy at high potential introduces a certain amount of impedance and introduces in the conductor a point at which the tendency for the current to leave the conductor is increased. To obviate this, we employ a 25 shunted connection 10 which eliminates the abrupt change in the direction of the conductor at the point of attachment to insulator.

The current passes through the metal or 30 line wire 8 which terminates in what is known as "a dead end" by its connection to the hook 1. Heretofore, the connecting line wire 9 has been attached to the wire 8 at its point of connection to the hook. In our 35 construction, we prefer to use a supplemental by-pass wire 10 connected to the wire 8, and also to the wire 9, so as to offer a straighter path for the current and in this manner avoid the abrupt turn at the connection between the wires 8 and 9. By doing this, we 40 believe that the tendency to "flashing over" will be minimized.

In operation, the static electricity will charge the shield 7 and by virtue of its proximity to the shield 5 will jump across the air space between the two shields. The heat generated in the shields by such sparking and by the sun will induce a current of air between the shields and the ionized air will 45 be carried away. By removing the ionized air, the tendency to "flash over" is reduced, and consequently, the value of the disk as an insulator is increased. Furthermore, we believe that where a current of air is induced between the shields that the tendency to sparking is also reduced.

The insulation disk, as shown in Fig. 2, is preferably provided with a series of concentric depressions in its faces for the purpose of increasing the leakage surface for

electricity over or across the faces of the disk.

What we claim is:

1. An electric insulator carrying a suspension member for supporting a conductor and provided with means for inducing circulation of air around the insulator, said means including a heat radiating member adapted for electrical connection with the conductor.

2. An electric insulator comprising attaching means and an interposed insulating disk, and metal shields insulated from each other disposed at the sides of said disk, said shields being spaced from the disk and from each other to provide inlet and outlet openings for circulating air currents.

3. An electric insulator comprising attaching means, an interposed insulating disk, and metallic elements arranged on each side of said disk and partially inclosing the same, the disposal of said metallic elements affording an outlet opening above the disk.

4. An electric insulator comprising attaching means, an interposed insulation disk, and bell shaped metal shields on each side of the disk which are spaced therefrom and from each other, said shields being cut away at their lower portions.

5. An insulator comprising the combination of an insulating member, a supporting member for the same, a suspension member carried by said insulating member for sustaining an electrical conductor, a shield attached to said suspension member and partially inclosing the insulating member, a complementary shield also partially inclosing the insulating member, said shields being insulated from each other and being formed to provide a considerable inlet opening adjacent the lower portion of the insulating member and outlet openings at the sides and above said insulating member, said openings providing passages for the circulation of air to and from said insulating member.

6. An insulator comprising an insulating member, a supporting member and a suspension member attached to said insulating member, and electrically conductive shield members spaced apart from the insulating member and disposed so as to transmit heat to the air surrounding said insulating member, the disposal of said shield members being such as to afford inlet and outlet passages so disposed as to direct air currents across said insulating member upon the heating of said disk members.

7. An insulator comprising an insulating member, a sustaining member attached to said insulating member and adapted to sustain an electrical conductor, a supporting member attached to said insulating member and comprising means for suspending the insulator, a shield capable of receiving a static charge attached to said suspension

member and disposed in proximity to the insulating member, and a coöperating shield of electrically conductive material supported on said supporting member in proximity to the insulating member, said shields forming an air chamber about said insulating member.

8. An insulator comprising an insulating member, a supporting member and a suspension member attached to said insulating member, the suspension member providing means for the attachment of an electrical conductor, a shield supported on the suspension member in proximity to the insulating member, and a complementary shield arranged in proximity to the insulating member and insulated from the first mentioned shield, said shields providing heat radiating and air guiding means about the insulating member.

9. An insulating device comprising the combination of an insulating member, an

electrical conductor supported therefrom, a shield member having electrical connection with the conductor and arranged in proximity to the insulating member, means for supporting the insulating member, and a second shield supported in proximity to the insulating member and insulated from the first mentioned shield, said shields providing an air chamber about the insulating member.

In testimony whereof, we have hereunto affixed our signatures in the presence of two subscribing witnesses.
